LOUVER ACTUATING AND FAN MOTOR
CONTROL MECHANISM

Emil A. Mader, Detroit, Mich., assignor of one-half to John Spargo, Detroit, Mich.

Application January 17, 1949, Serial No. 71,310

1 Claim. (Cl. 98—116)

1
This invention relates to louver actuating and fan motor control mechanism, an object of the invention being to associate with a set of louvers and a motor-driven fan inducing air flow through an opening controlled by the louvers, a normally open control switch for the motor, and means for automatically closing such switch upon opening the louvers.

Another object is to adapt a set of normally closed louvers to be opened by a mechanism suited to remote control, and to automatically set up a forced flow of air past the louvers, upon establishing their open position.

Another object is to provide an improved mechanism for establishing the open position of a set of normally closed louvers, such mechanism including a latch for holding the louvers in open position, and such latch being readily releasable by said mechanism.

Another object is to provide a quite simple and inexpensive mechanism for closing and opening a switch responsive to shifting of a set of louvers to their open and closed positions, such switch controlling the drive motor of a fan for inducing air flow past the louvers.

Another object is to provide an improved spring means for biasing a set of louvers toward their closed position.

These and various other objects are attained by the construction hereinafter described and illustrated in the accompanying drawings, wherein:

Fig. 1 is a top plan view of a set of louvers, with their frame and control mechanism, showing a closed position of the louvers.

Fig. 2 is a sectional elevational view thereof taken on the line 2—2 of Fig. 1, but showing an open position of the louvers.

Fig. 3 is an enlarged vertical sectional view taken on the line 3—3 of Fig. 1, showing a tubular arm and control parts associated therewith.

Fig. 4 is a vertical sectional view taken on the line 4—4 of Fig. 1, showing a mercury switch employed in the disclosed construction.

Fig. 5 is a sectional detail taken on the line 5—5 of Fig. 2, showing a spring connection between one of the louvers and a link bar.

Fig. 6 is an end view of a switch housing, showing the mounting of same on a post.

Fig. 7 is a bottom view of said post.

In these views, the reference character 1 designates a floor, such as that of an attic, formed with a rectangular air flow opening 2 defined by walls 3. For normally closing said opening there is installed in the opening a set

2
of sheet metal louvers 4 similarly pivoted at corresponding edges on rods 5 journaled in a frame 6 formed of angle iron. The louvers, when closed, lap each other in the usual manner, and are upwardly swung, when open. Midway of their length, they are pivotally interconnected by a link bar 7, engaging brackets 8 fixed on the louvers. From one of said brackets a pair of coiled springs 9, straddling the link bar, are extended to a bracket 10 upstanding on such bar, biasing the louvers toward their closed position.

The opening 2 is covered by an air flow housing 11 having an outlet 12 wherein is fitted a fan 13 for drawing air upwardly through the opening and expelling it through the outlet. The fan is driven through a belt 14 from a motor 15 whereof the circuit 16 is controlled preferably by a mercury switch (Fig. 4). The illustrated switch comprises the usual contact-receiving mercury bulb 17, occupying a housing 18, wherein said bulb is fixed on the upper end of a lever 19 pivoted between its ends at 20 and carrying a roller 21 below said housing. A coiled spring 22 acting on the upper end of said lever, tends to establish an open circuit position of the bulb 17, and the louvers 4, in their opening travel, serve to shift the bulb to its closed circuit position. Thus the roller 21 is engaged by an underlying louver 4 as the several louvers complete their opening travel, rocking the lever and mercury bulb to close the circuit.

It is preferred to rigidly surmount the housing 18 on a tubular arm or post 23 clamped by a U-bracket 24 to an end of the frame 6, such housing projecting above said underlying louver at a sufficient height to clear the latter in its opening travel. The arm 23 is further vitally useful in mounting mechanism for manually controlling the louvers. Thus the arm houses and guides a tubular slide piece 25, diametrically carrying a pin 26 to which is anchored a pull cord 27, upwardly extended beyond the post and over a pulley 28, and connected to the link bar 7 through a fusible link 29 and a coiled spring 30, disposed in end to end relation. Said pulley is journaled in a bracket 28a fixed on the upper portion of said arm. Also anchored to the pin 26 is the upper end of a latch bar 31 which slidably extends through a slot 32 centrally formed in a head 33 permanently closing the lower end of the post or arm 23. A pull chain or the like 34, of any convenient length, depends from the latch bar. The upper end 55 portion of said bar is cut away along one lateral

edge and thus forms a reduced tongue 35 inserted in the slide-piece. At the base of said tongue, the bar is formed with a latching shoulder 36, and when the slide-piece and bar are at their lower limit, corresponding to the open position of the louvers, such shoulder tends to underlie an end margin of the slot 32 so that a release of tension on the chain 34 results in seating the shoulder against such margin. Preferably said margin has a shallow rounded indentation 37 to receive and retain the shoulder. The tendency of the louvers to close, due to the springs 9, serves to urge the shoulder 36 into said indentation, when downward pull on the chain 34 is relieved. It is to be understood that the latch bar undergoes a slight lateral swinging on the pin 26 as soon as down travel of said bar exposes the shoulder 36 below the arm 23, such swinging disposing the shoulder in vertical registration with said indentation. Such lateral swinging results from fact that the pull chain attaches to the bar at its longitudinal axis, whereas engagement of the bar with the pin 26 is at the longitudinal axis of the tongue 35. It is obvious that a release of the latch bar may be effected by a slight swinging actuation of the pull chain.

The described mechanism assures that the fan will operate whenever the louvers are open and will be idle when the louvers are closed. Also it provides in a very simple manner for a common control of the louvers and fan motor. The disclosed provision for latching the louvers in open position or releasing same is extremely simple, inexpensive, and reliable in action. The spring 30 is of value in assuring a sufficient upward actuation of the latch bar, following a release of tension on the pull chain 34 to assure a firm latching engagement of the shoulder 36 with the margin of the slot 32.

While the mechanism has been described in its application to a floor-installed set of louvers, it is apparent that it is readily adaptable also to wall-installed louvers.

In mounting the switch housing 18 on the post 23, there is rigidly secured to the latter a laterally projecting arm 38 to which said housing is attached by bolts 39. It is preferred to form said arm with vertical slots 40 for said bolts whereby the switch housing may be raised or lowered to assure proper engagement of the roller 21 by various sizes of louvers.

What I claim is:

In a closure operating mechanism, a pivotal closure, a frame in which such closure is pivoted, such frame having an air flow opening, an elongated tubular arm, means rigidly securing said arm on said frame, a slide-piece slidable in said arm, an elongated flexible actuating element for the closure connected to the slide-piece, means operatively connecting said element to the closure, a pulley mounted on the tubular arm and guiding the actuating element, means for latching the slide-piece to the tubular arm in an open position of the closure, a fan mounted to deliver air through the opening of said frame, an electric motor driving the fan, a switch controlling such motor, means mounting the switch on said tubular arm, and a spring tending to open the switch, said switch having a control device in the opening path of the closure and actuatable by the closure in its opening travel to close the switch.

gated tubular arm, means rigidly securing said arm on said frame, a slide-piece slidable in said arm, an elongated flexible actuating element for the closure connected to the slide-piece, means operatively connecting said element to the closure, a pulley mounted on the tubular arm and guiding the actuating element, means for latching the slide-piece to the tubular arm in an open position of the closure, a fan mounted to deliver air through the opening of said frame, an electric motor driving the fan, a switch controlling such motor, means mounting the switch on said tubular arm, and a spring tending to open the switch, said switch having a control device in the opening path of the closure and actuatable by the closure in its opening travel to close the switch.

EMIL A. MADER.
